UNITED STATES PATENT OFFICE

2,405,874

ALKYLATION OF AROMATIC HYDROCARBONS

Edwin F. Bullard, Oakland, John Anderson, Berkeley, and Sumner H. McAllister, Lafayette, Calif., assignors to Shell Development Company, San Francisco, Calif., a corporation of Delaware

Application November 2, 1942, Serial No. 464,286

11 Claims. (Cl. 260—671)

1

This invention relates to the reaction of aromatic hydrocarbons with alkylating agents and particularly to the production of motor fuels and motor fuel components by alkylation of such hydrocarbons. It deals with an improved method for carrying out such alkylations whereby products having superior characteristics may be obtained.

An important object of the invention is to provide a more efficient and economical method of alkyllating aromatic hydrocarbons in the vapor phase. Another object is to improve vapor phase methods of reacting benzene and the like in the presence of solid acid alkylation catalysts. A further object is to increase the yield of desirable alkylation products by reacting aromatic hydrocarbons with olefins. Still another object is to produce aromatic alkylation products having superior properties, particularly as regards their motor fuel characteristics. Other objects and advantages of the process of the invention will be apparent from the following description.

Various methods of alkyllating benzene and higher aromatic hydrocarbons have been proposed from time to time, but they have not been successful because of their inefficient conversion of the starting materials and/or their poor quality of products. It has now been found that these disadvantages of prior alkylation methods may be overcome by the use of an improved reaction system employing, preferably, more advantageous reaction conditions.

The new process may be applied to the alkylation of a wide variety of aromatic hydrocarbons, although when used for the production of motor fuels or motor fuel components volatility considerations make it more advantageous to use lower boiling aromatic hydrocarbons, particularly benzene and toluene. Where such considerations are of lesser importance, higher boiling compounds may be employed. Thus, ethyl benzene, the xylenes, propyl or isopropyl benzene, mesitylene, the butyl benzenes, the cymenes, and homologues, naphthalene and its corresponding substitution products, and the like may be used. The source of the aromatic starting material is not important. The coal tar industry provides a convenient source of benzene, toluene, etc., but petroleum fractions containing these compounds, particularly the highly aromatic fractions obtainable by catalytic reforming or hydroforming, are also useful. Such fractions may advantageously be subjected to extraction with suitable solvents, for example, as described in U. S. Patent 2,114,524, to increase the concentration of the aromatic

2

hydrocarbon to be alkyllated before they are used in the process.

Alkyllating agents which may be used in the process include olefins, particularly suitable fractions of petroleum cracking products containing ethylene, propylene, isobutylene, normal butylenes, the amylene or mixtures of one or more such olefins. Instead of the olefins, polymers thereof may be used. Not only may ethers, alcohols and esters corresponding to the foregoing olefins be employed, but also other ethers, alcohols and esters, such as dimethyl, methyl-ethyl, methyl-isopropyl, di-normal propyl, ethyl-isopropyl and like ethers, methyl and higher primary alcohols, may be used. Either inorganic or organic esters such as halides, sulfates, phosphates, borates, formates, acetates and the like may be employed as alkyllating agents. The alkyllating agent may be used in a pure or substantially pure form or as mixtures of one or more alkyllating agents with or without other materials which do not interfere with the desired reaction.

As catalysts for the process, acids are used. 25 Most preferably the chosen acid catalyst is employed with a suitable carrier so that it may conveniently be used in solid form as packing for tower or tube type reactors. Acids of phosphorus are particularly suitable for this purpose, particularly mixtures of ortho or meta phosphoric acid or pyrophosphoric acid with kieselguhr or other suitable clays or earths such as are described in U. S. Patent 1,993,513. However, other catalysts such as sulfuric acid, hydrogen fluoride 30 or the like adsorbed on porous supports or as a coating or film on non-porous packing material or the like may also be used in the process. It is also feasible to employ liquid acid alkyllation catalysts in the process. 40 The alkylation is preferably carried out in the vapor phase with a substantial excess of aromatic hydrocarbons based on the alkyllating agent used. It has already been suggested that in alkyllating benzene an excess be used to suppress formation 45 of higher alkyllation products. Such excess benzene is not sufficient for most efficient reaction and it has been found desirable to use at least three, and more preferably five to ten or more, mols of the aromatic hydrocarbons being alkyllated per mol of olefin or equivalent alkyllating agent in the process of the invention. In this way not only are undesirable side reactions such as the formation of poly-alkylated products substantially eliminated, but also high conversions

of the alkylating agent to valuable products are obtained.

The reaction is most advantageously carried out under superatmospheric pressure; preferably pressures of 200 to 400 pounds per square inch are used. The temperature and time of contact which will be most desirable will depend upon the particular catalyst used and the alkylating agent chosen. For the alkylation of benzene with olefins such as propylene in the presence of phosphoric acid, a temperature of about 200° C. to 400° C., preferably about 250° C. to 300° C., and a hydrocarbon feed rate of about 0.1 to 0.8 gallon per hour per pound of catalyst are most advantageous. This combination of reaction conditions gives results which are markedly superior with respect to yields, conversions and efficiency of operation to those obtained by other methods.

It has previously been considered that alkylation of aromatic hydrocarbons accomplished a sufficient purification of the reactants and products so that no other treatment was necessary. However, to obtain the best results according to the present invention, it is desirable to treat the feed stocks used, especially the aromatic hydrocarbon, for removal of undesirable components, particularly sulfur-containing compounds such as thiophene, since otherwise these compounds undergo simultaneous reaction and appear in the product, materially reducing its quality especially for motor fuel use. Such treatment not only improves the quality of the product and simplifies its further processing, but also improves the effective life of the catalyst in the process.

For the treatment of benzene, for example, it is preferred to use sulfuric acid of about 90% to 100% concentration at a temperature of about 10° C. to 60° C., preferably about 98% concentration at about 20° C. A ratio of acid to benzene above 1 to 10 by volume is desirable and ratios of about 0.16:1 to 0.25:1 are preferred. The acid and benzene may be intimately contacted by agitation in a mixer or other vessel, countercurrent flow in a tower which may or may not contain packing to promote intimate mixing, or in any other suitable manner. A contact time of acid with benzene of at least 3 minutes, and more preferably 4 to 6 minutes or longer, is desirable. Contact in a plurality of reaction stages is advantageous in reducing the amount of acid required for treatment of a given volume of aromatic hydrocarbon. After the acid treatment the aromatic hydrocarbon is washed with a base such as aqueous caustic soda before being used in the alkylation step of the invention.

Merely treating the feed stocks before alkylation is not sufficient to obtain the best results in the present process. It has been found necessary to return to the sulfuric acid treating stage at least a part of the excess unreacted aromatic hydrocarbon recovered from the product. Since this aromatic hydrocarbon has been previously subjected to the sulfuric acid treatment as well as to the alkylating conditions, it would be thought that it would be ideal material for recycling directly to the alkylation and that further treatment could not possibly be of advantage. It was surprising therefore to discover that by feeding a part of this stream to the sulfuric acid treating unit instead of to the alkylation reaction, materially improved results, especially with respect to product quality, were obtained. The exact nature of all the changes in the recycle benzene or other aromatic hydrocarbon which are responsible for the improved results is not

known but it has been found desirable to submit at least one-tenth, and preferably at least one-fourth, of such aromatic hydrocarbon to treatment with sulfuric acid under the previously described conditions before returning it to the alkylation unit. The treatment may be effected along with or separately from the treatment of the initial feed.

The attached drawing shows, diagrammatically, an assemblage of apparatus particularly adapted for producing cumene by reaction of benzene with propylene according to the invention. In the drawing only the more important pieces of equipment are indicated for the most part, since the location of auxiliary equipment such as pumps, valves, storage tanks, pressure-, temperature- and flow-regulating and measuring devices, heat exchangers, and the like will be evident to those skilled in the art. In the arrangement of the drawing, benzene from a source not shown, is fed by line 1 to a mixer 2 in which it is contacted with sulfuric acid introduced via line 3. The resulting mixture passes by line 4 to settler 5 from which acid is taken off by line 6 and returned to mixer 2 by lines 7 and 3. A part of the acid may be continuously or intermittently withdrawn from the system by line 8. The partially treated benzene is conducted by line 9, together with fresh acid introduced by line 10, to mixer 11 where a further intimate mixing is effected. The resulting emulsion is taken by line 12 to settler 13 in which the acid and hydrocarbon phases are again separated. The separated acid is taken off by line 14 and a part returned to the second reaction stage by line 15 while the remainder is conducted to line 3 by line 16 to furnish the partially spent acid for the first reaction stage. The thus-treated hydrocarbon is fed by line 17 to mixer 18 which is supplied, continuously or intermittently, with a caustic from line 19. The caustic-benzene mixture is fed via line 20 to settler 21 from which caustic is withdrawn by line 22. The withdrawn caustic is returned to mixer 18 for further use by lines 23 and 17, a part being withdrawn as necessary by line 24. The treated benzene is taken off by line 25 and mixed with propylene or propylene-containing hydrocarbon which may advantageously have been caustic-treated in the same manner as the acid-treated benzene introduced via lines 26 and 27. Alternatively, the propylene may be introduced via lines 26 and 29 and thus be caustic-treated along with the benzene. In either case the mixture of propylene and treated benzene is conducted by line 29 to reactors 30 which are shown as a bank of tubes through which the reaction mixture flows in parallel. The reactors contain granules of phosphoric acid or other suitable acid catalyst not shown and are heated by steam or other means also not shown. They are preferably constructed to withstand pressures of the order of 1000 pounds per square inch. As previously indicated, however, other forms of reactors may be used and the reaction mixture may flow through two or more reactors in series instead of through all reactors in parallel as shown. Line 40 is provided for introducing steam or other activating or controlling agent as may be required to maintain the activity of the catalyst. It may also be used to introduce fresh catalyst or catalyst-regenerating agents.

The reacted hydrocarbon mixture, comprising cumene and unreacted benzene and propylene and any inert materials introduced with the feed or otherwise, is withdrawn from the reactors by

line 31 and conducted to depropanizer column 32 in which the lower boiling components are separated and taken off overhead by line 33. The remaining cumene and benzene are taken off as bottoms by line 34 and fed to debenziner column 35 from which the unreacted benzene is removed by line 36 and returned to the reaction by line 37 after withdrawal of a part of line 38 for treatment with sulfuric acid in mixers 2 and 11 along with the fresh benzene feed. The cumene produced is recovered by line 39.

The following examples further illustrate the advantages of the process, although no limitation on the invention is to be inferred therefrom as the same principles may be applied to the reaction of the same or other aromatic hydrocarbons with other alkylating agents.

Example I

To show the advantages of a high ratio of benzene to alkylating agent, a series of test runs were made with a solid phosphoric acid catalyst, using a reaction temperature of 200° C. to 250° C. and a pressure of 250 pounds per square inch. The hydrocarbon feed rate was 2000 grams per hour per liter of catalyst for each of the different benzene-propylene mixtures used. The following results were obtained:

Mol ratio benzene to olefin	Cumene in the product		Propylene converted
	Per cent	Per cent	
3.5 to 1	86	65	
5 to 1	90	90	
10 to 1	93	94	

Example II

The effect of pressure on the reaction was determined in a series of tests using a solid phosphoric acid catalyst and a feed containing 5 mols of benzene per mol of propylene.

Pressure (lbs. per sq. in.)	Feed rate (grams of hydrocarbon per hr. per liter of catalyst space)	Propylene concentration in the feed	Temperature	Propylene conversion	Cumene in the crude product
		Per cent	° C.	Per cent	Per cent
100	2,000	9.8	300-350	45	90
250	2,000	8.2	200-250	90	90
350	2,000	8.2	200-250	92	90
250	4,000	8.2	200-250	81	88
500	4,000	8.2	200-250	82	90

Example III

Effect of temperature was determined in comparative tests using a feed rate of 2000 grams of hydrocarbon per hour per liter of catalyst space, a benzene to propylene mol ratio of 5 to 1, and a pressure of 250 pounds per square inch. The propylene concentration in the feed was 8%-8.2%.

Temperature	Cumene in the product	Propylene converted
	Per cent	Per cent
175°-200° C.	90	60
200°-250° C.	90	90

The catalyst life under these conditions was of the order of 80 gallons of cumene per pound of catalyst. At higher temperatures the life decreases.

Example IV

The effect of sulfuric acid treatment of the benzene feed on the quality of the reaction products was shown by the following comparative runs made with coal tar benzene which was reacted with propylene in the presence of solid phosphoric acid catalyst using a reaction temperature of 200° C. to 250° C. and a pressure of 250 pounds per square inch. The benzene in one case was used directly and in the other case was treated with 25 pounds of 98% sulfuric acid per barrel at about 20° C. The molar ratio of benzene to olefin in each case was 5:1 and the feed rate was 1800 to 2000 grams of hydrocarbon per liter of catalyst per hour.

	Untreated benzene	Sulfuric acid-treated benzene
Sulfur in the benzene (wt. per cent)	0.47	0.06
Olefins in the benzene (wt. per cent)	0.76	0.09
Sulfur in the cumene (wt. per cent)	0.51	0.05

The propylene conversions and cumene yields for different periods of catalyst use were as follows:

Gallons of cumene produced per pound of catalyst at time of sampling	Using untreated benzene		Using sulfuric acid-treated benzene	
	Propylene conversion (wt. %)	Cumene in the product (wt. %)	Propylene conversion (wt. %)	Cumene in the product (wt. %)
1-2	86	88	88	90
3-4	74	87.5	88	89
5-6	47	87	88	89

The products were tested as 5% and 10% blends in 100 O. N. aviation gasoline with a final tetraethyl lead content of 4.0 cc. per gallon.

Rating in 3-C engine test

	Product from untreated benzene	Product from sulfuric acid-treated benzene
5% blend	Iso-octane+0.7 cc. of lead tetraethyl.	Iso-octane+1.1 cc. of lead tetraethyl.
10% blend	Iso-octane+1.1 cc. of lead tetraethyl.	Iso-octane+1.5 cc. of lead tetraethyl.

Copper dish gum (mg./100 ml.)

	Product from untreated benzene	Product from sulfuric acid-treated benzene
5% blend	5	1
10% blend	10	2

Considering the small amount of cumene in these blends, the effect of the sulfuric acid treatment of the benzene is seen to be remarkable.

Example V

Benzene was alkylated with isobutylene using the same apparatus as that employed in the preceding example. A catalyst temperature of 250° C. was used. The isobutylene conversion was 70% when using a 4.9 to 1 ratio of benzene to olefin, and 76%, using a 6.2 to 1 ratio.

With beta butylene in place of isobutylene, the conversion was 69% when using a 4.9 to 1 benzene to olefin ratio. In all cases the product contained about 85% butyl benzene and was practically free from olefin polymers.

We claim as our invention:

1. A process of producing cumene which comprises treating benzene with sulfuric acid of at least 90% concentration at about 10° C. to 60° C. for a time sufficient to reduce the thiophene content thereof, admixing the treated benzene with propylene in the ratio of 3 to 10 mols of benzene per mol of olefin and contacting the mixture under a pressure of between 250 and 600 pounds with a solid phosphoric acid catalyst at a temperature of 200° C. to 300° C. using a space velocity of 0.1 to 0.6 gallon of hydrocarbon per pound of catalyst per hour, fractionating the resulting products to separate unreacted benzene, and returning at least a part of the thus-recovered benzene to said sulfuric acid treatment for further reaction in the process.

2. A process of producing cumene which comprises passing a mixture of benzene and propylene in a molar ratio of at least 4 to 1 over a solid phosphoric acid catalyst at a temperature of 200° C. to 300° C. and a pressure of at least 250 pounds per square inch, separating at least a part of the unreacted benzene from the products, contacting at least a part of said separated benzene with sulfuric acid of at least 90% concentration, and returning the acid-treated benzene for further reaction in the presence of said phosphoric acid catalyst.

3. A process of producing cumene which comprises treating benzene with sulfuric acid of at least 90% concentration for a time sufficient to reduce the thiophene content thereof, reacting the acid-treated benzene with propylene in the presence of a solid phosphoric acid catalyst under a pressure of at least 250 pounds using a molar ratio of benzene to propylene of at least 4 to 1 and a temperature between 200° C. and 300° C., and recovering the resulting cumene.

4. A process of producing cumene which comprises contacting benzene with between one-tenth and one-fourth of its volume of sulfuric acid of 95% to 100% concentration for a period of 5 to 10 minutes at about 10° C. to 30° C. sufficient to materially reduce the thiophene content thereof, neutralizing the acid-treated benzene, and contacting a mixture of said benzene and an isopropylating agent containing at least three times the stoichiometric amount of benzene to isopropylating agent with a solid acid alkylation catalyst under alkylation conditions.

5. A process of producing cumene which comprises contacting benzene with concentrated sulfuric acid for a time sufficient to substantially reduce the thiophene content thereof, and reacting a molar excess of the resulting benzene with an isopropylating agent in the presence of a solid acid alkylation catalyst under a pressure of 250 to 600 pounds.

6. A process of producing cumene which comprises reacting a substantial molar excess of benzene with an isopropylating agent under a pressure of at least 250 pounds per square inch in the presence of a solid acid alkylation catalyst, sep-

arating unreacted benzene from the reaction products and contacting the separated benzene with concentrated sulfuric acid for a time sufficient to substantially reduce the thiophene content thereof, and returning the sulfuric acid-treated benzene to reaction with further isopropylating agent.

7. A process of producing an alkyl benzene which comprises reacting a substantial molar excess of benzene with an alkylating agent under a pressure of at least 250 pounds per square inch in the presence of a solid acid alkylating catalyst, separating unreacted benzene from the reaction products and contacting the separated benzene with concentrated sulfuric acid for a time sufficient to substantially reduce the thiophene content thereof, and returning the sulfuric acid-treated benzene to reaction with further alkylating agent.

10 8. A process of producing an alkyl benzene which comprises contacting benzene with concentrated sulfuric acid for a time sufficient to substantially reduce the thiophene content thereof, and reacting a molar excess of the resulting benzene with an alkylating agent in the presence of a solid acid alkylation catalyst under a pressure of 250 to 600 pounds.

15 9. A process of alkylating an aromatic hydrocarbon which comprises treating said hydrocarbon with at least one-tenth of its volume of concentrated sulfuric acid for a time sufficient to materially reduce the thiophene content thereof, and reacting a molar excess of the resulting aromatic hydrocarbon with an alkylating agent under a pressure of at least 250 pounds per square inch in the presence of a solid acid alkylation catalyst under alkylation conditions.

20 10. A process of alkylating an aromatic hydrocarbon which comprises treating said hydrocarbon with sulfuric acid of at least 90% concentration at 10° C. to 60° C. for a time of at least 5 minutes sufficient to materially reduce the thiophene content thereof, reacting a molar excess of the resulting aromatic hydrocarbon with an alkylating agent in the presence of a solid acid alkylation catalyst under alkylation conditions, separating unalkylated aromatic hydrocarbon from the reaction products, and returning at least a part thereof to said sulfuric acid treatment.

25 11. A process of alkylating an aromatic hydrocarbon which comprises reacting a molar excess of said hydrocarbon with an alkylating agent under a pressure of at least 250 pounds per square inch in the presence of a solid acid alkylation catalyst under alkylation conditions, separating unalkylated aromatic hydrocarbon from the reaction products and contacting at least a part thereof with sulfuric acid for a time sufficient to materially reduce the thiophene content thereof, and returning the thus-treated hydrocarbon to the alkylation reaction.
